UNITED STATES PATENT OFFICE.

FREDERICK FOSDICK, OF FITCHBURG, MASSACHUSETTS, ASSIGNOR TO THE FITCHBURG STEAM ENGINE COMPANY.

STEAM-ENGINE VALVE.

SPECIFICATION forming part of Letters Patent No. 279,484, dated June 12, 1883.

Application filed January 2, 1883. (No model.)

To all whom it may concern:

Be it known that I, FREDERICK FOSDICK, of Fitchburg, county of Worcester, State of Massachusetts, have invented an Improvement in 5 Steam-Engine Valves, of which the following description, in connection with the accompanying drawings, is a specification, like letters on the drawings representing like parts.

My invention relating to a steam-engine is 10 embodied in an engine of that class in which independent live-steam and exhaust valves control the flow of steam through the ports leading to each end of the cylinder.

The invention has for its object to enable 15 what is known as the "wrist-plate valve-gear" to be employed in connection with piston-valves controlling the admission of steam to the cylinder. With a wrist-plate valve-gear, or valve-gear in which the movement of the 20 eccentric is transmitted to one pin of a disk or crank-arm of a rock-shaft having two other pins or crank-arms connected with the valves at either end of the cylinder, the movements of the said valves are different, and they have 25 to be made independent of one another, so that when piston-valves are employed the steam in the steam-chest, with the usual arrangement, would press upon one side only of each independent piston-valve, which would thus 30 be unbalanced.

The present invention consists, partly, in providing a passage from the interior of the steam-chest at one end of each of the said piston-valves to the other end of the said valves, adding, if necessary, a bonnet or auxiliary chamber 35 to receive the steam from the said passage, and also to receive the said valves in their travel outward from the steam-chest. The steam thus acts upon both ends of each of the 40 said piston-valves with equal pressure, thus balancing each valve independently. The exhaust-valves may be connected together and operated directly from an eccentric on the engine-shaft in the usual manner, thus both having the same movement, and bonnets are 45 preferably provided to receive them in their outward travel. The live steam, acting as above described, upon both ends of the piston-valves, 50 equalizes the temperature of the said valves and the metal surrounding the valves through-

out their length, thus causing their expansion to be more uniform, and their operation consequently improved.

The invention also consists in details of construction of some portions of the engine, as 55 hereinafter specified.

Figure 1 is a plan view of a portion of an engine embodying this invention. Fig. 2 is a side elevation thereof; Fig. 3, a horizontal longitudinal section thereof on line *x* *x*, Fig. 60 2, the valve-actuating mechanism being shown in plan; and Fig. 4, a detail to be referred to.

The engine-cylinder *a* and its frame-work or bed-plate *b* may be of any usual construction, the latter containing the main shaft *c*, 65 upon which are mounted the eccentrics *d*, for actuating the valves. The eccentric *d*, for actuating the live-steam or inlet valves, is preferably made movable on the shaft, its position being controlled by a governor such as described in Letters Patent No. 221,296, November 4, 1879, granted to me, to which reference may be had. The eccentric-rod *f* of the said eccentric *d* is connected with a crank-pin, *g*, mounted on a crank fixed upon a rock-shaft, *h*, 70 provided with two other crank-arms, *i k*, the crank-pins of which are connected by links *m n* with the valve-rods *p o*, mounted in a guide, *r*, upon the bed-plate *b* of the engine. The valve-rod *o* is made tubular, and is connected 75 with a piston-valve, *o'*, controlling the flow of steam from the live-steam chest *s* into the port *t*, leading to one end of the cylinder *a*, while the other valve-rod, *p*, passes through the tubular valve-rod *o* and the live-steam chest *s*, and is 80 connected with the piston-valve *p'*, controlling the flow of steam from the said chest to the port *t'*, leading to the other end of the engine-cylinder. The valves *o' p'*, thus connected with the cranks *i k*, have an independent movement, 85 and are each acted upon at one side by the steam in the chest *s*. In order to equalize the steam-pressure upon each of the said valves *o' p'* independently, passages *u* are provided 90 leading from the interior of the steam-chest *s* to the other side of the cylindrical portion in which the valves *o' p'* travel, bonnets *v* being in this instance provided at either end of the steam-chest to receive the steam from the passages *u*, which thus acts equally upon both ends 95 100

of each valve $o' p'$, perfectly balancing the said valves and maintaining the temperature substantially uniform throughout their entire length. The valve-rod p is extended beyond the piston-valve p' , as shown at p^2 , passing out through the bonnet v at that end of the chest. The bonnets v are each provided with a tubular projection, v' , containing a hard bushing, v^2 , which serves as a guide and support for the valve-stems $o p$, the said tubular projection v' being also provided with a gland or stuffing-box, w , containing an annular chamber, w' , which is intended to be kept filled with oil for the purpose of lubricating the rods where they travel through the packing in the stuffing-box w and through the bushings v^2 . A small stuffing-box, w^2 , is provided at the end of the stuffing-box w , so as to prevent the escape of oil from the chamber w' along the rod o . A similar oil-receptacle, w^3 , and packing-box w^4 , are provided at the end of the tubular rod o , inclosing and lubricating the rod p , which passes therethrough, as shown in Fig. 4.

The valves controlling the flow of the exhaust-steam from the ends of the cylinders through the ports $t t'$ into the exhaust-chest R are connected together upon a single rod, and are actuated by a single eccentric-rod, e' , and eccentric e . Bonnets v are preferably provided for the said exhaust-valve, having similar bushings and stuffing-boxes for guiding, supporting, packing, and lubricating their valve-stems.

It is obvious that the chambered bonnets v might be omitted, the piston-valves then traveling wholly in the chest, the ends of which might be closed by ordinary heads; but by the employment of the said chambered bonnets it is possible for the ports $t t'$, leading to the ends of the cylinder, to be made straight, as shown, without making the steam-chest portion of the casting longer than the cylinder, and the short-

est and most direct passage possible for the steam is thus afforded and the clearance reduced to a minimum.

45

I claim—

1. The combination, substantially as shown and described, of the cylinder a , steam-chest s , steam-ports $t t'$, leading from the steam-chest to the cylinder, the piston-valves $o' p'$, operating independently upon the ports $t t'$, respectively, and the passages $u u$, connecting the steam-spaces on opposite faces of the piston-valves to balance said valves, as and for the purpose specified.

55

2. The combination, substantially as shown and described, of the valve-actuating eccentric and oscillating wrist-pins operated thereby, with the balanced piston-valves connected with and independently actuated by different ones of said wrist-pins, as and for the purpose set forth.

60

3. The combination, substantially as shown and described, of the piston-valves with a steam-chest, the external bonnets, v , communicating with said chest, and into which the valves move, and passages u , communicating between the steam-chest and said bonnets, and thereby admitting steam to both ends of and thereby balancing the valves, as and for the purpose specified.

65

4. The engine cylinder, steam-chest, and independent piston-valves, one having a tubular rod through which the rod of the other valve operates, combined with valve-actuating mechanism connected with the said rods, substantially as described.

70

In testimony whereof I have signed my name to this specification in the presence of two subscribing witnesses.

FREDERICK FOSDICK.
